INTERNAL COMBUSTION ENGINE

Herbert C. Edwards, Detroit, Mich., assignor to
 Packard Motor Car Company, Detroit, Mich., a
 corporation of Michigan

Application October 6, 1932, Serial No. 636,455

6 Claims. (Cl. 123—182)

This invention relates to internal combustion engines and more particularly to multi-bank cylinder engines of the type in which fuel and air are introduced separately into the combustion chambers.

An object of my invention resides in the provision of mechanism in a multi-bank cylinder engine which can be remotely controlled to relieve compression in one bank of cylinders where-by the crank shaft can be more easily turned in starting.

Still another object of my invention resides in mechanism for relieving compression in some of the cylinders of an internal combustion engine.

Other objects of the invention will appear from the following description taken in connection with the drawings, which form a part of this specification, and in which:

Fig. 1 is a fragmentary end view of a multi-bank radial engine, partly in section and partly broken away, having my invention incorporated therewith;

Fig. 2 is a fragmentary sectional view of the engine taken on line 2—2 of Fig. 3;

Fig. 3 is a vertical sectional view of the engine taken substantially on line 3—3 of Fig. 2;

Fig. 4 is a sectional view of the engine taken substantially on line 4—4 of Fig. 3 showing the mechanism for connecting the two sets of fuel control devices each of which is associated with one of the banks of cylinders;

Fig. 5 is a sectional view taken on line 5—5 of Fig. 3 illustrating a part of the actuating means for the compression relief mechanism;

Fig. 6 is a vertical sectional view of the engine taken on line 6—6 of Fig. 3 with the front end wall broken away;

Fig. 7 is a fragmentary view taken on line 7—7 of Fig. 6 illustrating rocker levers for actuating the fuel injection device and the inlet and exhaust valve operating mechanism.

Referring now to the drawings by characters of reference, the numeral 10 represents a barrel type crank case having a removable front end wall 11 and a removable rear end wall 12, such walls being secured to the crank case by means of bolts as indicated at 13. Within the crank case, I provide a pair of transversely extending walls 14 which are detachably secured in position by bolts as indicated at 15. Intermediate the walls 14 is another transversely extending wall 16 which has associated therewith studs 17 adapted to extend through the crank case. Extending axially of the crank case through the bearing portions of the walls 14 and 16 is a crank shaft

18 on the forward end of which is mounted a propeller for aeroplanes (not shown). Suitable roller bearings, as indicated at 19, are arranged in the walls 14 for carrying the crank shaft. The crank shaft is formed with a large circular bearing portion 20 which engages in the bearing portion 21 of the wall 16. On each side of the bearing portion of the crank shaft project crank pins 22.

The crank case is formed with two rows of 10 openings into which cylinders 23 extend, and such openings in the two rows are staggered relatively and thus there are two banks of radially extending cylinders, the cylinders in one bank being arranged intermediate the cylinders of the other bank, looking at the ends of the engine. The cylinders are formed with flanges 24 and around the forward ends of the flanges of the front bank of cylinders and the rear flanges of the rear bank of cylinders are provided hoop means, as indicated at 25, which are placed in tension greater than that developed therein by any forces developed in the engine during operation. Suitable means, such as a turn-buckle, indicated at 26, are employed for placing these hoops or bands in tension. The adjacent flanges of the cylinders in the two banks are formed so that they interfit and suitable crabs 27 engage adjacent edge portions of such cylinder flanges in the two banks. The studs 17 each project through a crab and nuts 28 are threaded on the studs and are screwed down to place the wall 16 and the studs 17 in tension greater than that developed therein by explosion forces in the cylinders. This manner of holding the cylinders upon a crank case forms the subject matter of my Patent No. 1,933,246 issued October 31, 1933, and no claim is made thereto in this application.

Pistons 29 are arranged for reciprocation in each of the cylinders and connecting rods 30 are pivotally carried by the master rod hubs 31, the master rods being connected to one of the pistons in each bank. This piston connection is of a conventional form and each hub encircles one of the crank pins 22.

The engine illustrated is of the four-stroke cycle type. The head of each cylinder is provided with an inlet valve 32 and an outlet valve 33 (Fig. 1) which control inlet and outlet passages extending through the head. These valves are normally closed by coil springs 34 which engage with retainers 35 secured on the valve stems and the valves are opened through the operation of rocker levers 36 which are actuated by tappet mechanisms or push rods 37 and 38 (Fig. 3), the

push rods 37 actuating the inlet valves and the push rods 38 actuating the outlet valves. The illustrated engine is of the Diesel type and air is admitted into the cylinders through the inlet passages and the exhaust gases leave the cylinders through the outlet passages. The piston heads are formed with a depressed end wall in order that they may closely approach the cylinder heads and, at the same time, have a clearance for the inlet and outlet valves. The combustion chambers are defined by the head portions of the cylinders and the end wall of their associated pistons.

Associated with each cylinder is a fuel injection device which consists generally of a nozzle section 39 and a pump section 40 (Fig. 1). The fuel injection devices for the front bank of cylinders are associated with the forward wall portion thereof while the injection devices for the rear bank of cylinders are associated with the rear-most wall portions thereof. The nozzle sections of the devices can be of any conventional character, however, Patent No. 1,690,893 of November 6, 1928 to Hermann Dorner can be referred to as a specific example. The pump section of each device consists of a casing 41 having a barrel portion 42 therein and a plunger 43 reciprocable in the barrel. The plunger includes an enlarged guide portion 44 which bears against the interior wall of the casing and is pressed toward the crank case by means of the coil spring 45 arranged within the casing. The casing and the barrel are provided with radially extending ports, as indicated at 46. A manifold 47 extends around each of the banks of cylinders and each is in communication with the ports 46 of the injection devices associated with the adjacent bank of cylinders. Oil is supplied to the manifold under low pressure by suitable pump means (not shown) so that, whenever the plungers 43 uncover the passages 46, the barrels will be open to the manifold and will be maintained full of oil. Thus when the plungers, on their injection strokes, close the ports 46, liquid fuel is trapped in the barrel and discharged under high pressure through the nozzle sections 39 into the cylinders. Associated with each of the pumps is an articulated push rod comprising sections 48 and 49. Suitable guide means, as indicated at 50, extend through the crank case and serve as the bearing for the push rod sections 48. The push rods for the devices associated with the rear bank of cylinders extend into a compartment 51 (Fig. 3) formed by the walls 12 and 14 while the push rods for the injection devices associated with the forward bank of cylinders extend into a compartment 52 in the crank case which is formed by the walls 11 and 14. The push rods for the valves associated with the rear bank of cylinders extend into the compartment 51 and the push rods for the valves for the forward bank of cylinders extend into the compartment 52.

The mechanisms for operating the push rods for the valves and the injection devices in each of the compartments are similar and therefore I will describe only one of such mechanisms. Fixed to the crank shaft is a gear 53 which meshes with a gear 54 carried by a shaft on which a gear 55 is fixed. Rotatably mounted on the crank shaft is a cam member 56 having an internal gear 57 which meshes with the gear 55. Such gearing provides a reduction drive from the crank shaft to the cam member which, in this instance, is an 8 to 1 ratio. Within each end compartment are

stud shafts 58 which are fixed to the walls 14. Each of such shafts has three rock levers 59, 60 and 61 pivotally mounted thereon and nuts 62 engage the shafts to secure the levers axially in position. Rock levers 60 are engaged by the 5 exhaust valve push rods 38, the rock levers 61 are engaged by the inlet valve push rods 37 and the rock levers 59 are engaged by the push rods 49 associated with the fuel injection devices. The rock levers 60 and 61 carry rollers 63 and the rock 10 levers 59 have abutments 64 associated therewith which bear against the cam members 56. Such cam members have three rows of lobes 56¹, 56², 56³ which rotate in zones to actuate the rock levers and thereby move them in a direction which imparts movement to the push rods for the valves and injection devices. 15

The outer faces of the rock levers 59 are formed with a groove 65 at the free end thereof which curves longitudinally, and the section 49 of the tappets for operating the fuel injection devices are slideable longitudinally of the levers in such grooves. Adjustment of the tappet sections toward the free end of the associated rock levers will lengthen the plunger stroke after closing the ports 46, while movement toward the pivoted ends of the rock levers will decrease the plunger stroke and thus the quantity and timing of the fuel charges can be regulated. Rotatably carried by each wall 14 is a ring 66 and links 67 pivotally connect each of the tappet sections 49 with the adjacent ring. On the rear ring is fixed a rack 68 (Fig. 1) with which a gear 69 is in mesh, and this gear is fixed on a shaft 70 which extends through the crank case 10. An arm 71 is fixed to the projecting end of the shaft carrying the gear 69 and mechanism, as indicated at 72, is associated with the arm so that it can be rotated from a distance. Rotation of the rear ring 66 will shift the contact position of the tappet sections of the injection mechanism for the rear bank of cylinders, and thus the stroke of the plungers 43 after closing the passages 46 will be varied and likewise will vary the time of closure. Thus the rear injection devices can be simultaneously regulated both as to quantity of the delivered charges and the time of delivery relative to the piston position. 45

It is desirable that the front ring 66 operate uniformly and simultaneously with the rear ring so that all of the injection devices can be regulated similarly and together by a single manipulation upon the part of the operator. To this end, I arrange a rock shaft 73 within the crank case between two of the cylinders in the rear bank and pivotally mount it in the wall 16 and the rear wall 14 with an end extending into the rear compartment. An arm 74 is fixed at one end to the rock shaft and in the rear compartment and is pivotally connected to a bracket 75 fixed on the ring 66 by an adjustable link 76. Another rock shaft 77 extends within the crank case between two cylinders of the front bank and is pivotally mounted in the wall 16 and the front wall 14, the front end of the rock shaft extending into the front compartment. The rear end of the rock shaft 77 has an arm 78 fixed thereto which is connected by a link 79 to an arm 80 fixed to the rock shaft 73. The front end of the rock shaft 77 has an arm 81 fixed thereto which is connected by a link 82 to a bracket 83 fixed on the front ring 66. The mechanism just described is all contained within the crank case and will move the front ring simultaneously and uniformly with 75

the rear ring so that the position of the front tappet sections 49 will be varied in the same manner as the similar rear tappet sections.

In starting a multi-bank engine, it is desirable to relieve the compression in a plurality of the cylinders when the engine is of the compression-ignition type and I prefer to relieve the compression in the entire group of cylinders in one of the banks through a single operation. To this end, the rock levers 61 of the inlet valve control mechanisms for the front bank of cylinders are each formed with a boss 85 (Fig. 6) arranged to co-operate with a cam ring 86 located adjacent the front row of cams 56. Carried on the free ends of the front shaft 68 is a circular plate 87 which is secured in axial position by the nuts 62. The plate is formed with curved slots 88 through which supporting pins 89 extend, such pins being secured at one end to the cam ring 86 and having a head at the other end of larger diameter than the width of the slots 88. Secured to the cam ring 86 is a bracket 90 having fixed thereto a bifurcated member 90' which is engaged by the arm 91 extending from a bell crank 92 which is mounted upon a stub shaft 93 extending from a bracket 94 fixed to the front wall 14. To another arm 95 of the bell crank is pivotally connected a rod 96 which extends rearwardly through the front wall 14. This rod 96 is also pivoted to a sleeve 97 (Fig. 5) which is swiveled on a shaft 98 extending across an opening in the wall 16, and also pivoted to the sleeve 97 is a rod 99 which extends rearwardly of the crank case through the rear wall 12 of the casing. A suitable mechanism, as indicated at 102, is connected with the link 100 so that the compression relief mechanism can be controlled from a distance, such as from the cockpit of an aeroplane.

Reciprocation of the link 100 will move the rod 99 therewith which will rock the sleeve 97 on its pivot 98 and will move the rod 96 in a reverse but parallel direction to that in which the rod 99 is moved. Reciprocation of the rod 96 will rotate the bell crank 92 and the arm 91 will be rotated and move the bracket 90 therewith. The cam ring 86, being fixed to the bracket 90, will be moved therewith so that the lobes 86' on such cam ring will be brought into a position whereby they engage the bosses 85 on the rock levers 61 or whereby they disengage the same, such movement being limited when the pins 89 reach the ends of the slots 88. As the lobes on the cam ring are brought into engagement with the rock lever bosses, they tend to rotate the same on their pivots and, when moved in one direction, the push rod mechanisms 37 will be moved outward radially to move the associated intake valves and, when moved in the other direction, they will be moved inward radially allowing the said inlet valves to close. It will thus be seen that, when starting the engine, or if at any other time it is desired to relieve the compression in the front bank of cylinders, the cam ring 86 is moved in a counter clockwise direction, as viewed in Fig. 6, to engage the rock levers so that the air inlet valves will be held open and it is moved in a clockwise direction from such position when compression relief is not desired. Engagement of the lobes 86' of the cam ring 86 with the bosses on the levers 61 will hold the associated valve mechanism in open position so that the cam lobe 56³ will not engage

them, and thus there can be no compression developed in the front bank of cylinders.

It will be seen that I have provided mechanisms actuated by a single operation for simultaneously and similarly regulating the quantity of the fuel charges and the time of their delivery with respect to the position of the piston in the cylinders of a multi-bank engine. It will also be seen that I have provided mechanisms which can be controlled by a single operation for relieving the compression in the front bank of cylinders while still allowing explosions in the rear bank of cylinders. Both of these mechanisms can be operated from a point remote from the engine so that they can be readily controlled from the cockpit of an aeroplane when the engine is used in this connection. The compression relieving mechanism, with the exception of the extension, is wholly enclosed within the crank case and is arranged so that it will operate readily irrespective of the staggered relation of the cylinders in the two banks.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In an engine having a crank case and a bank of radially extending cylinders, each of said cylinders having a valve controlled passage, a cam actuated mechanism for opening each of the valves including a rock lever, shafts in the crank case on which the rock levers are mounted, a ring member secured on the shafts, a cam ring having lobes adapted to engage the rock levers to hold the valves in open position, a movable support for the cam ring carried by the ring member, and means for rotatably regulating said cam ring to move the lobes into or out of engagement with the rock levers.

2. In an engine having a crank case and a bank of radially extending cylinders, each of said cylinders having valve controlled passages, a cam actuated means for holding a valve of each cylinder in open position, a cam ring engageable with said means for holding the valves in open position, regulating means for moving the cam ring into or out of position in which the valves are held open, a support in the crank case for said cam ring, and movable actuator connections between the cam ring and the regulating means.

3. In an engine having a crank case and a bank of radially extending cylinders, each of said cylinders having a valve controlled passage, a mechanism for opening each of the valves including a cam actuated rock lever, shafts fixed in the crank case on which the rock levers are mounted, a ring member fixed on the shafts, said member having arcuate slots therein, a cam ring having lobes adapted to engage and lift the rock levers to hold the valves open, pins fixed to the cam ring and extending through the slots in the ring member, and means for rotating the cam ring to move the lobes into or out of engagement with the rock levers.

4. In an engine of the character described, a crank case having aligned compartments formed by transverse walls, a bank of cylinders extending radially from one compartment of the crank case, each of said cylinders having a valve controlled passage, mechanism for opening each

- of the valves, said mechanisms each including a cam operated rock lever in a compartment of the crank case, a rotatably adjustable cam ring having lobes adapted to engage the rock levers to hold the valves open, and means extending through the compartments for regulating the rotatable position of the cam ring.
5. In an engine, a plurality of banks of radially extending cylinders, each of said cylinders having an air inlet passage, a crank shaft, pistons in the cylinders connected to the crank shaft, valve means for the air inlet passages, means operated by a moving part of the engine for opening said valve means, and means engageable with 10
15 the inlet valve opening means for each cylinder

of one bank of cylinders to maintain the inlet passages open.

6. In an engine, two banks of radially extending cylinders, each of said cylinders having an air inlet passage, a crank shaft, pistons in the cylinders connected to the crank shaft, valve means for the air inlet passages, means operated by a moving part of the engine for moving said inlet valve means to open position, a cam ring engageable with said inlet valve opening means associated with the cylinders in one bank to hold said opening means in open position, and means for rotating said cam ring to regulate its relation with said valve moving means.

HERBERT C. EDWARDS. 15
